WINDOW CONSTRUCTION

Stephen M. Casey, Oakland, Calif.

Application May 15, 1950, Serial No. 162,126

2 Claims. (Cl. 20—36)

1

This invention relates to new and useful improvements in window construction and constitutes an improvement over my Patents No. 1,507,158, issued September 2, 1924, and No. 2,288,936, issued July 7, 1942. Said patents relate to a window having vertically slidable sashes supported in a frame which may be inserted in a door and particularly in place of a wood, glass or window-screen panel, such as frequently occupies the upper half of a door. By the use of such a window construction it is possible to install the equivalent of a standard window in a standard door or to convert an existing standard door for such purposes. Such window construction employs a pair of sashes, each vertically slidable in a frame, the frame being provided with individual slideways for each sash. Thus, each may be individually raised and lowered by hand in order to control the amount of ventilation through the door. When the sashes are both closed, the window is substantially weather and water tight and when the two sashes are properly adjusted a maximum amount of ventilation is obtained, for the reason that an opening substantially equal to one-half the area of the panel is left unobstructed.

The particular feature which comprises the improvement of the present invention is a resilient mounting of the frame in the door. Thus, the sash frame is held in the door by resilient means whereby the frame may be removed when desired by compressing the spring means between the mounting and the sash frame, thereby making possible the removal of the frame from the door. This feature makes possible the removal of the frame when the door is being painted inasmuch as the frame is customarily constructed of aluminum which is not improved either in appearance or weathering ability by painting. The resilient mounting of the frame is also of importance if it is desired to replace the frame by a solid panel or by a window-screen panel at certain seasons of the year.

Another feature of the resilient mounting is that each individual sash may be removed from the frame by springing the frame outwardly so as to permit the inner edge of the sash to escape from the slideway in which it is confined. This feature is desirable if it is necessary to replace the glass in one of the sashes.

The resilient mounting further makes it possible to employ a frame of standard size which may be fitted into doors having panels which vary slightly in dimensions inasmuch as the resilient mounting compensates for such varia-

2

tion in dimensions of the panels which are replaced by said mountings.

The resilient mounting further automatically compensates for warping or swelling of the door due to dampness and prevents the frame from rattling due to vibration.

In the drawings:

Fig. 1 is an elevation of the window construction installed in a door, the door being partly broken-away.

Fig. 2 is a horizontal section taken substantially along the line 2—2 of Fig. 1.

Fig. 3 is a horizontal section taken substantially along the line 3—3 of Fig. 1.

Fig. 4 is a horizontal section taken substantially along the line 4—4 of Fig. 1.

Fig. 5 is a vertical section taken substantially along the line 5—5 of Fig. 3.

Fig. 6 is a fragment of a corner of the window construction.

Fig. 7 is a vertical section taken substantially along the line 7—7 of Fig. 8.

Fig. 8 is a vertical section taken substantially along the line 8—8 of Fig. 1.

The present invention is designed for use in connection with the standard door 10, such a door commonly having a panel which occupies substantially the entire upper half of the door.

In standard doors, such a panel is frequently made of wood or glass and sometimes of window-screen. In the present invention the window construction which is the subject of the present invention is installed in place of a panel, thereby dispensing with the wood, glass or window-screen. It will be understood that the window construction which is the subject of this invention may be installed at other locations in a building structure, but the invention finds its greatest usefulness in the purpose heretofore set forth.

The window construction employs an upper sash 11 and a lower sash 12, each vertically slidable within the guide 13. As illustrated herein each sash is provided with a glass light 14 of substantially rectangular shape. About each of the four edges of the said glass light is a U-shaped reinforcement 16 which protects the edge of the glass, thereby preventing damage to the glass or injury to anyone who may contact the same.

One leg 16a of the reinforcement is longer than the other leg 16b. The bottom of the U is filled with a piece of wood 15 and the glass is held within the reinforcing edge by means of putty 17 inserted between the reinforcement 16 and the glass 14 at one side of the glass. Glazer's points

15a are imbedded in the wood 15 at appropriate points to hold the glass in place, and the adjacent reinforcing edges at the sides and upper and lower ends of the sash are held together by rivets 19 which pass through the reinforcing edges 16 and also through metal corner strips 21 disposed at the corners of the sash. The side reinforcing strips 16 are arranged to fit within channel-shaped guide members 13 which extend vertically of the frame and provide slide-ways 22 and 23 for the upper and lower sashes, respectively. It will be understood that the reinforcing member 16 and slideways 22 and 23 are complementary in shape and are dimensioned so that the sash may easily be slid vertically with respect to the frame, but, nevertheless, a substantially weather-tight fit is obtained. Vertical guide members 13 are formed substantially E-shaped in cross-section as shown particularly in Figs. 2, 3 and 4. The upper sash 11 may be disposed within the channel 22 and the lower sash 12 disposed within the other channel of the E-shaped guide member 13. Thus, the upper and lower sash may be individually raised or lowered by hand without interference one with the other and thereby the degree of ventilation through the window construction may be controlled.

It will be understood that a plurality of notches 29 may be cut out of the side guide members 13, said notches receiving spring biased latch members 31 carried by the reinforcing edges 16 of the sash. This construction resembles that shown in my Patent No. 2,288,936. The sash may be held in various positions of adjustment by permitting the latch members 31 to engage the notches 29, whereupon the sash will be held in position until the latch members are manually retracted by manipulation of finger grips 32 connected to said latches and the sash raised or lowered to a new position of adjustment.

The side guide members 13 are received within the open ends of substantially U-shaped channel mounting members 36. The distance between the parallel sides 37 of the mounting member 36 is substantially equal to the thickness of the side guide member 13, but the side guide members 13 are sufficiently smaller so that they may slide within the mounting member 36 but the fit is close enough so that the window is air and water tight.

Substantially one-third of the way below the top and one-third of the way above the bottom of the mounting member 36 is a spring 38, substantially helical in configuration, one end of the spring being fixed to the base 39 of mounting 36 and the other end bearing against the guide member 13, all as most clearly shown in Figs. 3 and 5. The inner end of spring 38 is fixed to base 39 by means of a rivet 41 passing through the base 39 and having a washer 42 at its opposite end which engages one of the coils of spring 38. The opposite end of the spring 38 is free, but bears against the guide member 13. Thus, the spring urges the guide member 13 and mounting member 36 apart, but the force of the spring 38 is weak enough so that the guide member 13 may be readily slid within the channel 36, thereby compressing the spring 38.

The top mounting member 46 is formed as a shallow channel extending across the top of the window. The bottom mounting member 47 which extends across the bottom of the window is substantially flat with an upwardly bent flange 75

48 disposed on the outside of the window which prevents water from leaking under the frame.

The slide mounting members 36 and the top and bottom mounting members 46 and 47 are held together by slot-and-pin connections. Thus, a yoke 49 is riveted to the lower mounting member 47 as best shown in Fig. 7, said member 49 being slidably received within the channel-shaped side mounting member 36. An elongated pin 51 passes through apertures in each of the legs 52 of the yoke-shaped member 49 and extends through horizontal slots 53 in the lower end of the side mounting member 36. Yoke-shaped member 49, bottom mounting member 47 and the outwardly-bent flange 50 of frame 13 are all fixed in position by rivets 55 passing therethrough. Each of the heads 54 of said pin 51 is enlarged so that the pin 51 may not be disengaged from the side mounting member 36. Within the limits of the length of the slot 53, the side mounting members 36 may be moved laterally with respect to the bottom mounting members 47. It will be understood that a similar slot-and-pin connection attaches the upper end of the side mounting member 36 to the top mounting member 46.

The mounting member is held in the door by reason of the fact that the outer longitudinal surface of the base 39 of the side mounting member 36 is provided with a central longitudinal rib 56 and lesser ribs 57 longitudinally extending along each corner. A conventional door panel is held in place by means of a pair of molding strips 58 which are spaced apart to provide a gap 59 having the thickness of a wood panel or a piece of glass which may ordinarily occupy a conventional door panel. The central rib 56 of the mounting member 36 is of a thickness substantially equal to the width of said gap 59, i. e., of a wood panel or glass pane and thus, the molding strips 58 hold said rib 56 in position as best shown in Figs. 2 and 4. The corner ribs 57 bear against said molding strips 58 and assist in holding the mounting in position.

Installation

Assuming that a conventional door 10 is to be fitted with a window construction which is the subject of the present invention, the molding strips 58 at the top and bottom of the panel are permanently removed. Molding strips 58 at the sides are temporarily removed to permit withdrawal of the glass or wood and then replaced. The workman manually compresses the side mounting members 36 toward each other so that the central rib 56 at each side may pass over the high points of the molding strips 58 along the sides of the panel. This compression is made possible by reason of the fact that the springs 38 compress and the side guide members 13 slide within the channels which make up the side mounting members 36. With the central rib 56 in position in gap 59 between the molding members 58 the springs 38 snap the side mounting members 36 in position. It will be understood that the top mounting member 46 fits snugly against the top of the panel opening and that the bottom mounting member 47 fits snugly against the bottom of the panel. It will be observed, therefore, that the installation is simple and requires no special tools or extraordinary skill.

With the window in position, as weather conditions require, the bottom and top half of the sash may be raised or lowered to afford the required degree of ventilation.

If it should be necessary to remove the entire window, as when the door is being painted or for any other purpose, the upper sash 16 is lowered halfway and the lower sash 12 is raised halfway so that two sashes overlie each other. The workman then grasps one of the side mounting members 36 and pulls the same inwardly toward the center of the panel. This operation compresses the opposite side guide member 13 inwardly into the channel of its side mounting member 36. Thereupon the central rib 56 of the first side escapes from within the gap 59 between the molding strips 58 which hold it in place and thus the entire window may be lifted out of the door.

When it is necessary to remove only one sash, as when the pane of glass has been broken, the two sashes 11 and 12 are moved to the same position overlying one another as heretofore described, the sash 12 to be removed is grasped and moved sidewise, thereby compressing the opposite side guide member 13 into the open channel of the opposite side mounting member 36. This operation is continued until the reinforcing edge 16 escapes from the channel 23 of the guide member 13, and thereupon the sash 12 may be lifted out but the other sash 11 and the entire mounting 36, 46, 47 and guide 13 are left in position.

The ease and rapidity with which the window may be installed and removed or an individual sash installed and removed is one of the important features of the present invention. This feature has particular utility when the mounting, frame and reinforcement 16 are made of aluminum inasmuch as it is undesirable to paint such material. The ease with which the sashes 11 and 12 may be removed from the guide 13 makes it possible to transport the sash to a glazer for replacement of panes.

Although I have described my invention in some detail by way of illumination for purposes of clarity of understanding, it is understood that certain changes and modifications may be made therein without departing from the spirit of the invention or scope of the appended claims.

I claim:

1. A vertically-slidable, plural window sash construction for installation in an opening in a door, a door side frame member defining said opening of said door, at least two moldings on said door side frame member having a groove therebetween, said window construction comprising, a pair of substantially U-shaped channel

mounting members disposed on opposite sides of said opening, each of said channel members having its open side facing toward the center of the door and having at least three ridges projecting upwardly from its opposite side, the intermediate ridge fitting within said groove, a pair of sash side guide members, each of said sash guide members being slidably received in one of said channel members, each of said sash guide members being shaped as a double channel with the open sides facing toward the center of the door, resilient means biasing adjacent channel mounting members and sash guide members apart, means restraining said sash guide members within the openings of said channel mounting members, and a pair of vertically slidable window sashes, one of said sashes having its side edges received within one of the channels of said guide members and the other said side having its side edges received within the other of said channels, said sashes being slidable parallel to each other.

2. A window construction according to claim 1 which further comprises a top and a bottom horizontal mounting member fitting against the top and bottom edges of said opening, and slot-and-pin connections connecting each end of each of said horizontal mounting members to one of said channel mounting members, one of said horizontal mounting members having longitudinal ribs.
